SELF ADJUSTING AND EXPANDING PLUG FOR WELLS AND THE LIKE

Filed Feb. 23, 1929

Robert J. Schuyler, INVENTOR
BY Loyd J. Miller, ATTORNEY

UNITED STATES PATENT OFFICE

ROBERT J. SCHUYLER, OF DUNCAN, OKLAHOMA, ASSIGNOR TO FRANK SHIPLEY, OF LAWTON, OKLAHOMA

SELF ADJUSTING AND EXPANDING PLUG FOR WELLS AND THE LIKE

Application filed February 23, 1929. Serial No. 342,224.

My invention relates to self adjusting and expanding plugs for oil and gas wells, and the like.

The objects of my invention are to produce a device of this class which will be new, 5 novel, practical, useful and of utility; which may be positioned at any point in the well; which does not require the well to be filled up from the bottom to the point at which the plugging is desired; which prevents the dissolution of cement in a well by the entering of outside liquid or gas; which will prevent outside water from mixing with oil and gas therein and forming an emulsion; which 10 may be detached and left within the well; which will at times prevent the loss of an entire oil field; which will help confine the product of an oil field to that particular field; which, when permanently positioned, 15 will be immovable without its destruction; which may be temporarily positioned by air pressure; which will allow the cementing of the well at points within the well where chemical action and liquids prevents the 20 hardening of concrete; which will allow the cementing of a well at points within the well where gas pressure agitation usually prevents the hardening of concrete; which may 25 be used for locating breaks in the casing of a well; which will be simple, strong and durable in operation; which will prevent the loss 30 of a well; which will be efficient in accomplishing all of the purposes and uses for which it is intended.

At the present time considerable difficulty is encountered in drilling oil and gas wells because of the fact that there are some structures encountered which contain chemicals adverse to the hardening or setting 35 process of concrete. Many times a driller or drilling company finds a sand containing a small amount of oil, and if he were certain that he could successfully plug the well below it, he would drill on down in search of 40 larger production, but not being certain, he stops at the smaller production.

The breaking of the casing often occurs in drilling wells. This usually allows outside water to enter the well which causes in many 45 instances the entire loss of the well.

There are many instances where the strata upon which the bottom of the well casing is seated, caves away and fails to support the weight of the casing. If this happens directly above producing strata, the well below 55 the bottom end of the casing cannot be cemented to make a seating because doing so would also cement off the production.

My invention is so constructed that it may be cemented in position at any point in the well. Chemical action or gas pressure agitation cannot hinder the hardening of the cement. It gives the driller assurance that he is taking no chance of losing what production he has, by drilling past it in search 65 of some greater production. He knows he can at any time return to the desired point in the well and plug up and use the producing sand below which he has drilled.

By taking out the valves in my invention, 70 and using air pressure instead of cement, my invention may be used for locating the exact point in the well where a break in the casing has occurred. My plug may be temporarily positioned at various depths in the well, 75 until it is discovered at what point the casing is leaking. When the casing seat of a well is lost, my invention may be cemented in a position just below the casing end without the danger of cementing off any production, 80 because the cement is confined within the device. The well would not have to be cemented from its bottom up to the bottom of the casing.

All metal parts of my invention except 85 the spring and bolts are preferably made of cast iron. This allows more easily its drilling out when it is desired.

In oil and gas well drilling, salt water is 90 one of the hardest elements to control. There have been instances where a whole section of an oil field has been lost because it was not possible to properly shut off the flow of salt water in one well. Salt water rising in a well 95 may enter a strata which is not producing in that particular well, and flow therethrough to some producing well in the locality. This of course ruins the production in the other well, and at times several wells in the vicinity. Not only is considerable expense and time 100

spent in trying to shut off salt water, but there have been instances where the pressure was so great that adjacent wells have had to be drilled into the salt water bearing strata, 5 expressly for the purpose of relieving the pressure to the extent that they might be plugged. Salt water has been known to reach through an oil well to the fresh water strata of a locality and ruin the water wells for 10 great distances around the oil well. In all of the above mentioned instances the damage and expense could have been eliminated in a few hours by the use of my invention.

With these and other objects in view as 15 will more fully appear my invention consists in the construction, novel features, and combination of parts hereinafter more fully described, pointed out in the claims hereto appended, and illustrated in the accompanying 20 one-sheet of drawings, of which,

Figure 1 is an elevational view of my invention showing the fabric casing collapsed about it ready for lowering into the well; Fig. 2 is a sectional view through my invention showing it positioned in the bottom of a well.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

In drilling, it frequently occurs after the 20 surface casing has been set and before the permanent casing is set that a strata is drilled into that carries a high pressure of water or gas. In many cases of this kind when the surface is closed, the pressure below it is so great that the water or gas forces itself to the surface between the walls of the well and the surface casing. This particular form of breakage is extremely difficult to stop. In cases of this kind my device may be positioned below the bottom end of the surface casing and above the pressure bearing strata. This will allow the reseating and the cementing of the casing so as to prevent the escape of oil and gas thersurrounding. The plug 25 may then be drilled through and the hole continued.

A practical embodiment of the invention as illustrated in the drawings includes:

A vertical check valve 1 of any standard or 30 known make, having left hand threads 2 at its upper aperture and right hand threads 3 at its lower aperture. Said valve 1 is adapted to threadedly connect with a like size tubing or drill stem 4 of an oil well drilling outfit. Said tubing 4 bears left hand

threads at the end which connects said valve 1. Said valve 1 is adapted to open with the exertion of a downward pressure through said tubing 4 and to close when upward pressure is applied to the bottom aperture thereof. Threadedly connected to the bottom aperture of said vertical valve 1, I provide a heavy duty nipple 5. Threadedly positioned around the outside surface of said nipple 5, and adjacent the upper portion and 70 at a point adjacent the lower extremity of said valve 1, I provide a metal perforated disc 6. Said disc 6 has formed therethrough and adjacent its outer portion a plurality of holes 7 and 8. Around the outer surface of 75 said nipple 5 but not threadedly connected thereto, I provide a plurality of metal perforated discs 9, 10, 11, 12 and 13 preferably made of cast iron. The upper disc 9 of said discs 9, 10, 11, 12 and 13 being the largest and 80 each disc therebelow graduating in size, each smaller than the one above it with said disc 13 being the smallest. Around the outside surface of said nipple 5 and positioned between and extending outwardly beyond said 85 metal discs 9, 10, 11, 12 and 13, I provide a plurality of fabric discs 14, 15, 16, 17 and 18. The upper disc 14 of said fabric discs being the largest and each disc therebelow being graduated in size, each smaller than the one 90 above it, with said disc 18 being the smallest. Said discs 14, 15, 16, 17 and 18 are of any suitable material, but are preferably of gaudy canvas belting. Said disc 14 being positioned between said perforated metal 100 disc 6 and said disc 9, said fabric disc 15 being between said metal discs 9 and 10, said fabric disc 16 being between said metal discs 10 and 11, said fabric disc 17 being between 105 said metal discs 11 and 12 and said fabric disc 18 being positioned between said metal discs 12 and 13. Through all of said metal discs 9, 10, 11, 12 and 13 and through all of 110 said fabric discs 14, 15, 16, 17 and 18, and in vertical alignment below the said holes 7 and 8 in said perforated disc 6, I provide a plurality of perforations for receiving connecting bolts 19 and 20. Said bolts 19 and 20 are provided on their upper ends with nuts 115 21 and 22. Depending from the lower portion of said bolts 19 and 20 and below said metal disc 13, I provide metal housing 23. Said metal housing 23 is provided at its upper extremity with flange 24. Said flange 24 having a plurality of perforations 120 spaced to coincide with the perforations through said disc 13. Said perforations through said flange 24 are for the purpose of receiving said bolts 19 and 20. The body of 125 said housing 23 is tubular in shape, and has adjacent its upper portion and made integral therewith a lateral portion 25 dividing said housing 23 into two compartments. The upper compartment 26 being a valve chamber for a lateral valve. Upon the inside wall 130

of said valve chamber 26 is formed a guiding lug 27 having a cylindrical cavity in the end thereof for receiving valve stem 28. Through the side wall of said valve chamber 26 and oppositely positioned from said lug 27, is formed an opening 29. The edges of said opening form a valve seat for seating valve head 30. Around said valve stem 28 is retrieving spring 31 which has one of its ends rigidly connected by any means to said lug 27 and its other end connected through a lateral perforation 32 in said valve stem 28. Within the lower chamber 31 of said housing 23 I provide a metal stem 32, having adjacent its upper end an enlarged cylindrical portion 33 which acts as a traveling guide for said stem 32 within said chamber 31. Said enlarged portion 33 of said stem 32 is adapted to closely fit within and to vertically slide within said chamber 31. Over the upper end of said stem 32 and having its lower end resting against the upper end of said enlarged portion 33, and having its upper end resting against the lower side of said partition 25, I provide compression spring 34. Threadedly connected over the lower end of said housing 23 and fitting around the smaller portion of stem 32, I provide bushing cap 35. Said bushing cap being adapted to allow therethrough a vertical movement of said stem 32 and to retain said enlarged portion 33 within said chamber 31. Threadedly attached or made integral with the lower end of said stem 32, I provide a metal disc 36. Said disc 36 is provided adjacent its outer portion with a plurality of perforations, (not numbered), for receiving clamping bolts 37 and 38. Said bolts 37 and 38 are provided with clamping disc 39 which has perforations therethrough for receiving said bolts 37 and 38. Said bolts 37 and 38 are further provided with nuts 40 and 41 for tightening said disc 39 toward said disc 36. Around the outside of said housing 23 and said stem 32 and extending longitudinally from the upper end flanged portion of said housing 23 to the bottom surface of said disc 36, I provide a plurality of resilient envelopes or tubes 42 and 43. Said tube 43 being slightly larger than and fitting over the outside surface of said tube 42. Around the entire outside surface of said tube 43, I provide a fibrous envelope of tube 44. Said envelope 44 is made in two sections 45 and 46. The upper section 45 being thicker adjacent points shown as 47 and 48, near its upper end. Said upper section 45 of said envelope 44 extends downwardly inside of said lower section 46 to points shown at 49 and 50. The lower section 46 of envelope 44 is thicker adjacent points shown as 51 and 52 near its lower end. Said lower section 46 of said envelope 44 extends upwardly on the outside of said upper section 45 to points shown as 53 and 54. Said resilient tubes 42 and 43 are

to be made of rubber or any suitable resilient material. Said envelope 45 to be made of canvas or any suitable fibrous material.

It will be seen that when said nuts 21 and 22 are tightened upon said bolts 19 and 20, that all of said metal discs 6, 9, 10, 11, 12 and 13, and all of said fibrous discs 14, 15, 16, 17 and 18, and the upper ends of said resilient tubes 42 and 43 the upper end of said envelope 44, and the flanged end of said housing 23, will all be clamped firmly and held rigidly together. It will also be seen that when nuts 40 and 41 are tightened, that the lower ends of said tubes 42 and 43 and envelope 44, will be clamped tightly and held firmly between said discs 36 and 39.

For use when my device is being lowered into a well, I provide a plurality of bands 55, 56, 57, 58, 59, 60, 61 and 62, better seen in Fig. 1, for holding said tubes 42 and 43 and envelope 44 collapsed flatly around said housing 23 and said stem 32. Said bands 55, 56, 57, 58, 59, 60, 61 and 62 are made of rubber or any suitable material, and are of such strength that they will break under a few pounds pressure.

In operation my device is lowered on stem 4 to the desired point in the well. Cement or a cementitious substance is then forced under pressure through said tubing 4, through said vertical valve 1, through said nipple 5 out through said lateral valve chamber 26, and opening 29, into the interior of said tube 42. As tube 42 fills with the cement it breaks the bands 55, 56, 57, 58, 59, 60, 61 and 62 on the outside of envelope 44, and forces said envelope 44 outwardly against the sides of the well hole. It will readily be seen that if there is a cavity in the side of the well wall at the point where the plug is being installed, that the outward pressure of the cement will force the said envelope 44 into the said cavity. It will also be seen that the said outward pressure will exert an upward pull on the bottom of said stem 32, which will travel upwardly in said housing 23 and allow said envelope 44 to completely fill the said cavity. The thicker portions 47 and 48 of said envelope 44 will, when internal pressure is applied thereto, push upwardly against the fibrous discs above and against the well wall and fill any crack between said fibrous discs and said well wall. It will also be readily seen that when my device is positioned at the conjunction of a well hole and a smaller rat-hole, that the fibrous discs will seat at the junction point. Stem 32 if placed upon the bottom of the rat-hole may travel upwardly in said housing 23 and allow said fibrous discs to descend and seat as desired. After my plug has been positioned at any desired point in a well, it may be detached at the point between said tubing 4 and said vertical valve 1, because of the left hand threaded connection between said tubing 4 and said vertical valve 1. Pressure

will be held within my device after it is disconnected by said lateral valve or said vertical valve 1, or both.

It will further be seen when said envelopes are being filled with said cementitious substance, that the lower portion thereof will, due to gravity, be filled first, and that as they fill to a point past the middle thereof that they are exerting a frictional hold on the well walls. It will also be seen that when a great pressure is exerted upon the flowing cementitious substance that the hold would be so great that the entire plug would be immovable even though the well wall was practically smooth. Those familiar with the art know that well walls are never extremely smooth and that the well wall is usually more or less rugged. In considering this it will be seen what a tremendous friction hold my plug will have upon the well walls.

Obviously, the invention is susceptible of embodiment in forms other than that which is illustrated in the accompanying drawings and described herein, and applicable for the uses and purposes other than as detailed, and I therefore consider as my own all such modifications and adaptations and other uses of the form of the device herein described as fairly fall within the scope of my invention.

Having thus described my invention what is claimed and desired to be secured by Letters Patent, is:

1. A plug, as described, for plugging a well, adapted at its top for removably connecting the lower end of a tubing or a drill stem thereabove, means for anchoring same in said well, resilient means adapted for connecting said anchoring means and for being laterally inflated within said well and for receiving a cementitious element, means for automatically vertically adjustably positioning said resilient means, and means for protecting said resilient means.

2. A plug, as described, for plugging a well, adapted at its top for removably connecting the lower end of a tubing or a drill stem thereabove, means for anchoring same in said well, resilient means adapted for connecting said anchoring means and for being laterally inflated within said well and for receiving a cementitious element, means for vertically adjustably positioning said resilient means, outside means for protecting said resilient means having thinner lapping ends adjacent its center for spreading and for producing a friction grip.

3. A plug, as described, for plugging a well, adapted at its top for removably connecting the lower end of a tubing or a drill stem, its upper end adapted to snugly fit in a rat-hole and against the side walls in said well, a metallic slidable stem adjacent its lower end, a flanged housing for said stem adapted to depend from said upper end, said slidable stem having an enlarged upper por-

tion for movably seating in the lower end of said housing, a compression spring within said housing for adjustably positioning said slidable stem, a resilient envelope, of a suitable material and an outer envelope of a suitable material for encasing said resilient envelope, said resilient envelope and said enclosing outer envelope adapted for automatic vertical adjustment and for lateral expansion within said well, means for introducing a cementitious element within said resilient envelopes, said resilient envelopes with said cementitious element therein and said enclosing envelope adapted to fill and hermetically seal said well at a desired position.

4. A well plug embodying a normally deflated resilient bag adapted at its upper end for removably connecting to the lower end of a tubing, means for anchoring said bag in a well, a hollow cylinder within said bag and attached at its upper end to the upper end of said bag, a piston mounted slidably within said cylinder, the lower end of the piston rod connected to the lower end of said bag, a spring within said cylinder for normally holding said piston in the lower end of the cylinder, and means for introducing a cementitious substance within said bag.

5. A well plug embodying a normally deflated resilient bag adapted at its upper end for removably connecting to the lower end of a tubing, means for anchoring said bag in a well, a hollow cylinder within said bag and attached at its upper end to the upper end of said bag, a piston mounted slidably within said cylinder, the lower end of the piston rod connected to the lower end of said bag, a spring within said cylinder for normally holding said piston in the lower end of the cylinder, means for introducing a cementitious substance within said bag, and enclosing means for protecting the exterior of said bag.

6. Organization as described in claim 5, in which said enclosing means comprises a pair of fibrous envelopes, one enclosing the upper portion of the bag and the other enclosing the lower portion of the bag, said envelopes telescoped one into the other at substantially medially of said bag in a manner permitting a slippage between the envelopes when the bag is filled.

7. A well plug embodying a normally deflated resilient bag adapted at its upper end for removably connecting to the lower end of a tubing, means for anchoring said bag in a well, a hollow cylinder within said bag and attached at its upper end to the upper end of said bag, a piston mounted slidably within said cylinder, the lower end of the piston rod connected to the lower end of said bag, a spring within said cylinder for normally holding said piston in the lower end of the cylinder, means for introducing a

cementitious substance within said bag, encasing means for protecting the exterior of said bag, and breakable means for holding said bag and said encasing means 5 closely around said cylinder and piston rod when said bag is empty.
